FOLDABLE CHAIR

Milton L. Tinsley, Grantwood, N. J., assignor to
 Ferguson Brothers Manufacturing Company,
 Hoboken, N. J., a corporation of New Jersey

Application November 5, 1932, Serial No. 641,356

5 Claims. (Cl. 155—141)

This invention relates to improvements in foldable chairs, and has for an object to provide a chair which can be readily and compactly folded and which can be quickly and easily unfolded for use.

Another object of the invention is to provide a foldable chair which, when in unfolded position, will present all the characteristics and appearance of a conventional non-foldable chair, and which will be rigid and solid when in use.

Another object is to provide a foldable chair of simple and practical construction which will be automatically locked when brought to its unfolded position.

A further object is to provide means for releasing the locking mechanism, which means is actuated simultaneously with the upward movement of the seat.

A still further object is to provide certain improvements in the form, construction and arrangement of the parts whereby the above named and other objects may effectively be attained.

A practical embodiment of my invention is represented in the accompanying drawings, in which

Fig. 1 represents a front elevation of my improved chair in its unfolded position, as in use;

Fig. 2 represents a detail side elevation of the seat and adjacent parts;

Fig. 3 represents a vertical section taken in the plane of the line III—III of Fig. 1, looking in the direction of the arrows; Fig. 3* represents a detail vertical section, on an enlarged scale, of the bracing and locking mechanism of the front legs.

Fig. 4 represents a bottom plan view of the chair, on the same scale as shown in Figs. 1 to 3 inclusive;

Fig. 5 represents a front elevation of the chair in its folded position;

Fig. 6 represents a side elevation of the same; and

Fig. 7 represents a vertical section taken in the plane of the line VII—VII of Fig. 5, looking in the direction of the arrows.

The back 1 of the foldable chair is secured between the upper ends of vertically disposed side members 2, 3 which extend downwardly and form the rear legs 4, 5, respectively. A substantially rectangular seat 6 is provided with side frames 7, 8 and a front frame 9. Angle plates 10, 11 are fixed to the inner walls of the side frames 7, 8 by screws 12 or other similar means. The short arm 13 of the plate 10 is arranged to extend beyond the frame 7 and upwardly therefrom so as

to be hingedly connected with a pin 14 secured to project inwardly from the member 2. The plate 11 also has a similar short arm 15 which hinges on a pin 16 on the side member 3. By the arrangement of the angle plates 10, 11 with respect to the side frames 7, 8 and members 2, 3, the seat 6 may be swung upwardly adjacent with the members 2, 3 to a folded position and, when in unfolded position, the rear ends of the side frames will rest solidly against the front face 65 of the members 2, 3.

The front legs 17, 18 are also hingedly connected to the front portion of the side frames 7, 8 by means of plates 19, 20, respectively, of which one end of the plate 19 is secured to the upper end 70 of the leg 17 by screws or other suitable means, and the other end fulcrumed on a pin 21 fixed to project inwardly from the inner wall of the side frame 7 and spaced from the front frame 9 of the seat. The plate 20 has one end secured to the upper end of the leg 18 by screws or other suitable means, while the other end is connected with a pin 22 carried by and projecting inwardly from the inner wall of the side frame 8. The hinged connections of the front legs 17, 18 are disposed in position to allow a portion of the front and side frames of the seat to rest upon the top of the legs when in use, as shown in Figs. 1 to 3 inclusive. This arrangement of the hinged connections of the front legs and seat likewise adds 75 to the general characteristics and appearance of a non-foldable chair.

A transverse bar 23 connects the legs 17, 18, the ends of which bar are pivoted in the legs at 24, 25. A similar transverse bar 26 is disposed between 80 the rear legs 4, 5 with the ends of the bar pivoted at 27, 28. The transverse bars 23, 26 are connected by braces 29, 30 so as to move simultaneously.

In order to lock the front legs 17, 18 and the seat 6 in their unfolded position, I provide a detent 31, the outer ends 32, 33 of which are flattened and pivoted at 34, 35 to the legs 17, 18, respectively. This detent 31 has a straight central portion 36 which is arranged to swing into and out of an arcuate notch 37 and move in a longitudinal slot 37* connected with the mouth of the notch. The notch 37 and slot 37* are formed in a guide block 38 fixed to the under side of the seat 6. To facilitate the movement of the straight portion 36 of the detent in the notch 37, the walls of the notch are curved concentrically with the pivots 34, 35 of the detent when the legs 17, 18 are in their unfolded position. To remove the portion 36 of the detent from the 100 105 110

notch 37, I provide a lever 39 having a finger piece 40 at its front end and its rear end pivoted at 41 to the guide block 38. This lever 39 is arranged to extend forwardly toward the front 5 of the seat 6 so as to be within easy reach of the operator for the manipulation of the detent. In order to prevent the unintentional displacement of the straight portion 36 of the detent in the notch 37, I provide a flat spring 42 having one 10 end 43 fixed to the bottom of the seat 6 and arranged to extend into the longitudinal slot 37* with its free end 44 disposed to normally close the mouth of the notch 37. A stop and guide 45 is fixed between the guide block 38 and the 15 bottom of the seat 6 to limit the movement of the lever 39 in one direction and locate its position ready to actuate the straight portion 36 of the detent when desired.

When it is desired to fold the chair for storage 20 or transportation, the finger piece 40 and lever 39 under the seat are manipulated to engage and lift the straight portion 36 of the detent 31 out of the notch 37 and depress the spring 42 against the seat 6, so that the portion 36 may 25 slide rearwardly in the slot 37* in the guide block 38 and the front of the seat swung upwardly on its hinged connections 14, 16 between the members 2, 3, in which movement the front legs 17, 18 are swung on the pins 21, 22 in the side frames 30 of the seat, while the detent is rocked on its pivots 34, 35 on the legs 17, 18. The straight portion 36 of the detent after passing the spring 42 is free to slide rearwardly in the longitudinal slot 37* in the guide block 38. In the upward 35 movement of the seat, the front legs are maintained in a substantially vertical position by the braces 29, 30 fixed to the transverse bars 23, 26 and the pivotal connections of the bars in the front and rear legs so that, when the 40 chair is in the folded position, the seat will rest against the back and the front legs intimately contact with the bottom of the seat. Thus the chair, when folded, has the front legs, seat, back legs and members extending substantially 45 parallel to one another in very close arrangement and occupying a relatively small space. When it is desired to bring the chair to its unfolded position, as in use, the seat is swung outwardly on its pivots 14, 16, in which movement the front legs swing outwardly and downwardly while the detent 31 oscillates on its pivots 34, 35 on the front legs 17, 18 causing the straight portion 36 of the detent to ride forwardly in the longitudinal slot 37* until it engages the 50 spring 42, which will be depressed until the straight portion registers with and enters the curved notch 37 whereupon the front legs will be locked against movement. In this position the rear ends of the side frames of the seat 55 will abut the front face of the members 2, 3, and a portion of the front and side frames will rest upon the top of the front legs 17, 18. It will thus be seen that the chair when in operative position will present all the characteristics and appearance of the conventional non-foldable chair.

It will be understood that various changes may be resorted to in the form, construction and arrangement of the several parts without departing from the spirit and scope of my invention; and hence, I do not intend to be limited to the details herein shown and described except as they may be included in the claims.

What I claim is:

75 1. In a foldable chair, a combined back and

rear leg frame, a seat having side frames pivotally connected to said rear leg frame, front legs hinged to said side frames of the seat, an element fixed to depend from the under side of said seat and having a longitudinal slot adjacent the seat terminating at its forward end in a notch, a detent comprising sides having its ends pivoted on said front legs and converging rearwardly to a straight central portion disposed in position to slide in said slot by the movement of the legs and engage said notch in the element for bracing and locking the seat and front legs against movement when the chair is in its unfolded position, a spring device disposed with its free end overhanging said notch for urging said straight central portion of the detent into the notch, and means pivoted on the element for actuating the straight central portion of the detent against the tension of said spring device to release it from its engagement with the notch in the element and the seat and front legs from their locked position.

2. In a foldable chair, a combined back and rear leg frame, a seat having side frames pivotally connected to said rear leg frame, front legs hinged to said side frames of the seat, a detent comprising sides having its ends pivoted on said front legs and converging rearwardly to a straight central portion, and an element fixed to depend from the under side of said seat and having a longitudinal slot adjacent the seat terminating at its forward end in a notch, the walls of said notch being parallel and curved concentrically with the pivots of the detent when the legs are in their unfolded position, whereby said straight central portion of the detent may be disposed in position to slide in said slot by the movement of the front legs and arranged to swing on its pivots on the front legs into the notch and engage one of the curved walls of the notch for bracing and locking the seat and front legs against movement when the chair is in its unfolded position and maintained in said notch by gravity.

3. In a foldable chair, a combined back and rear leg frame, a seat having side frames pivotally connected to said rear leg frame, front legs hinged to said side frames of the seat, a detent comprising sides having its ends pivoted on said front legs and converging rearwardly to a straight central portion, an element fixed to depend from the under side of said seat and having a longitudinal slot adjacent the seat terminating at its forward end in a notch, the walls of said notch being parallel and curved concentrically with the pivots of the detent when the legs are in their unfolded position, whereby said straight central portion of the detent may be disposed in position to slide in said slot by the movement of the front legs and arranged to swing on its pivots on the front legs into the notch and engage one of the curved walls of the notch for bracing and locking the seat and front legs against movement when the chair is in its unfolded position and maintained in said notch by gravity, and means pivoted on the element and adapted to engage said straight central portion of the detent to release it from its engagement with the notch in the element and the seat and front legs from their locked position.

4. In a foldable chair, a combined back and rear leg frame, a seat having side frames pivotally connected to said rear leg frame, front legs hinged to said side frames of the seat, a detent comprising sides having its ends pivoted on said

- front legs and converging rearwardly to a straight central portion, an element fixed to depend from the under side of said seat and having a longitudinal slot adjacent the seat terminating at its forward end in a notch, the walls of said notch being parallel and curved concentrically with the pivots of the detent when the legs are in their unfolded position, whereby said straight central portion of the detent may be disposed in position to slide in said slot by the movement of the front legs and arranged to swing on its pivots on the front legs into the notch and engage one of the curved walls of the notch for bracing and locking the seat and front legs against movement when the chair is in its unfolded position and maintained in said notch by gravity, and a spring device disposed in the longitudinal slot with its free end overhanging the entrance to said notch for urging the straight central portion of the detent past the entrance of the notch.
5. In a foldable chair, a combined back and rear leg frame, a seat having side frames pivotally connected to said rear leg frame, front legs hinged to said side frames of the seat, a detent comprising sides having its ends pivoted
- on said front legs and converging rearwardly to a straight central portion, an element fixed to depend from the under side of said seat and having a longitudinal slot adjacent the seat terminating at its forward end in a notch, the walls of said notch being parallel and curved concentrically with the pivots of the detent when the legs are in their unfolded position, whereby said straight central portion of the detent may be disposed in position to slide in said slot by the movement of the front legs and arranged to swing on its pivots on the front legs into the notch and engage one of the curved walls of the notch for bracing and locking the seat and front legs against movement when the chair is in its unfolded position and maintained in said notch by gravity, means pivoted on the element and adapted to engage said straight central portion of the detent to release it from its engagement with the notch in the element and the seat and front legs from their locked position, and a spring device disposed in the longitudinal slot with its free end overhanging the entrance to said notch for urging the straight central portion of the detent past the entrance of the notch.
